CLAIM

The ornamental design for a burner for gas range, as shown and described.

DESCRIPTION

1. Burner for gas range

1.1 is a perspective view of a burner for gas range showing our new design;

1.2 is a front elevation view thereof;

1.3 is a rear elevation view thereof;

1.4 is a left-side elevation view thereof;

1.5 is a right-side elevation view thereof;

(Continued)

1.6 is a top plan view thereof;
1.7 is a bottom plan view thereof; and
1.8 is another perspective view thereof, in a use condition.
The broken lines in the drawing figures are included for the purpose of illustrating environment and form no part of the claimed design.

1 Claim, 8 Drawing Sheets
